PAGE 2

FIG. 1 is a perspective view of a combined wheel and brake drum showing my new design;

FIG. 2 is a diametrical cross-sectional view thereof;

FIG. 3 is a perspective view of a modified form of the combined wheel and brake drum shown in FIG. 1;

FIG. 4 is a diametrical cross-sectional view thereof;

FIG. 5 is a perspective view of another modified form of the combined wheel and brake drum shown in FIG. 1; and

FIG. 6 is a diametrical cross-sectional view thereof.

The dominant features of my design reside in the portions shown in full lines.

This application is a continuation of my copending applications Serial Nos. D. 67,708, D. 67,710, and D. 67,711 filed November 27, 1961 and now abandoned.

I claim:

The ornamental design for a combined wheel and brake drum, substantially as shown and described.
